(57) **CLAIM**

(21) Appl. No.: **29/173,619**

The ornamental design for a support line clamp for boat
accessories, as shown and described.

(22) Filed: **Jan. 2, 2003**

DESCRIPTION

(51) LOC (7) Cl. **08-08**

FIG. 1 is a front view of a support line clamp for boat

(52) U.S. Cl. **D8/387**

FIG. 2 is a right side thereof, the left side view being a mirror

(58) Field of Search D8/387; 114/230.23;
403/110; 411/378-379, 387.4, 389, 397

image

FIG. 3 is a top view thereof, this view having one of a pair
of threaded clamping nuts removed for clarity of the illus-
tration, the bottom view being a mirror image thereof; and,
FIG. 4 is a right side view of FIG. 3 and showing an interior
beveled face of each of the threaded clamping nuts.
